(57) **CLAIM**

The ornamental design for an automobile and toy replica thereof, as shown and described.

DESCRIPTION

FIG. 1 is a front perspective view of an automobile and toy replica thereof showing my new design;

FIG. 2 is a rear perspective view thereof;

FIG. 3 is a front elevational view thereof;

FIG. 4 is a rear elevational view thereof;

FIG. 5 is a top plan view thereof; and,

FIG. 6 is a right side elevational view thereof, the left side elevational view being a mirror image thereof except for the door over the gas cap which is not present on the left side, and the windshield wipers that are not symmetrical.

1 Claim, 5 Drawing Sheets
